UNITED STATES PATENT OFFICE

2,408,142

COMB

Ernest L. Hollenbeck, Glendale, Calif.

Application September 24, 1945, Serial No. 618,211

3 Claims. (Cl. 132—11)

1

The primary object of my invention is to provide a comb having two relatively disposed parallel rows of teeth in staggered relation to each other, and equally adapted to both right and left handed persons.

A further object is to provide a comb which in its combing effect offers every advantage of a fine toothed comb, yet more readily providing a free and easier passage of the teeth through the hair and without the customary tooth breakage more or less common with fine toothed combs.

A further object is to provide a comb with its teeth disposed so that the strands of hair separated by the first row of teeth in contact therewith will be simultaneously acted upon by the teeth of the second row, and whereby unison of the combing action is obtained in a more highly flexing manner as the teeth weave through the hair, and this, regardless of the number of comb strokes employed.

A still further object is the provision of a comb of said characteristics which may be cut, stamped, molded or otherwise produced, and from any suitable material readily lending itself to the production of combs.

And a further object is the provision of a comb presenting a novel combination and arrangement of the toothed sections to facilitate the removal of foreign matter in the process of cleansing the same, and whereby the respective parallel rows of teeth may be separately handled in the cleansing process, yet remain firmly fixed in attached relation with one another.

I attain these objects with the comb illustrated in the accompanying drawing in which:

Figure 1 is a front elevation of the comb in closed position;

Figure 2 is an elevation similar to Fig. 1 but with the comb in open position;

Figure 3 is a section on line 3—3 of Fig. 1.

Figure 4 is a section on line 4—4 of Fig. 1, and

Figure 5 is a view of the toothed edge of the comb in the closed position.

Similar letters and numerals of reference indicate like parts throughout the several views. Thus the comb is designated in general as 10. It is provided with the conventional comb handle 11 which is integrally formed with a comb-back 12 provided with a plurality of teeth 13 which are herein termed coarse as opposed to the term applied to a fine tooth comb.

The longitudinal axis of the back 12 is offset so that the longitudinal axis of the handle 11 lies along the side of the back 12 thereby providing space for another comb-back 14 having its longi-

tudinal axis offset so that the longitudinal axis of the handle 11 lies along the side of the back 14 or in other words between opposing sides of the back 12 and the back 14.

5 The back 14 is also provided with a plurality of teeth 15 of the same degree of coarseness as the teeth 13. The back 14 is not provided with a handle integral therewith but is connected by a rivet 16 to the back 12 in a manner herein-10 after described which permits teeth 13 and teeth 15 to be used as one comb by grasping the handle 11.

The rivet 16 also acts as a pivot permitting the teeth 15 carried by the back 14 to be turned away 15 from the teeth 13 carried by the back 12 for the purpose of cleaning said teeth. See Fig. 2.

A channel shaped clip 17 is secured by a rivet 18 to the handle 11 adjacent the junction of the handle 11 and the back 12. One end of the clip 20 17 overlies the back 12 with one side of the clip imbedded in a depression 19 provided in the back 12 and the other side of the clip 17 spaced from the back 12 to permit the entrance of one 25 end of the back 14 when said back is pivoted about the rivet 16 to the closed position of the comb 10 as seen in Fig. 1.

A depression 20 is provided in the end of the clip 17 which is also embedded in a depression 21 provided in the handle 11 so that the outside 30 of the clip 17 is flush with the outside of the handle 11 and the outside of both backs 12 and 14. The clip 17 also provides added and desirable strength, support and stiffness for the comb assembly at this junction.

35 A boss or projection 22 is provided on the back 12 on the side adjacent the side of the back 14 and approximately midway between the rivet 16 and the clip 17. The boss 22 is designed to seat in a cavity or depression 23 provided on the side 40 of the back 14 whenever the end of the back 14 is moved beneath the clip 17 thereby snap locking the comb 10 in the closed position of Fig. 1 due to the resiliency of the comb material and the tension provided by the snap locking means 45 aforesaid.

It will be noted in Fig. 1 and more especially in Fig. 5 that when the comb 10 is in the closed or combing position the teeth 13 are in staggered relationship to the teeth 15 so that a brushing action as well as a combing action is practicable. Note separation of hairs indicated at H as comb 10 is moved to the left as seen in Fig. 5. There is thus provided a coarse toothed comb functioning as a fine toothed comb, and offering every 55 advantage of the latter without its common draw

backs, the breaking of teeth, for example, coupled with the difficulty in pulling the comb through snarled and otherwise heavy hair. The staggered tooth arrangement in the specific manner of the placement of the teeth as shown, moreover serves to unsnarl the hair due to the flexing and weaving action of the brushing effect experienced as the comb passes through the hair, however light or heavy that may be.

Readily produced from materials obtainable in the open market, and at no great cost, the invention offers a simple embodiment of a dual row of teeth pivotally engaged to one another; light in weight, and requiring no special consideration in its use from that employed in using a comb of the common single toothed row variety. Moreover, the double row of coarse teeth in preference to fine teeth completely eliminates the customary breakage of teeth inherent in a fine toothed comb during the cleaning process.

To clean the comb, the pivoted back section is swung clear of the main or stationary section, whereupon either or both comb sections may be readily cleaned as is the ordinary single section comb.

As numerous different embodiments and changes in construction, style and shape of this invention could readily be made without departing from the scope thereof as herein shown and described, it is intended that the description and drawing shall be interpreted as illustrative and not in a limiting sense.

What I do claim, however, as new and novel and desire to secure by Letters Patent is:

1. In a comb, two parallel disposed back sections provided with separate rows of teeth, one of said back sections in pivoted engagement with the other of said back sections, a securing member juxtaposed in secured relation with said last named back section for embracing and holding said pivotally engaging back section in combing relation with the other said back section, said

5 pivotally affixed back section having a depression formed therein, and said first named back section having a projection outstanding therefrom and integrally therewith arranged to slidably move over and in contact with the other back section and then enter said depression, and providing a snap locking means for securing said pivotally affixed back section against involuntary dislodgement from said securing means.

10 2. In a comb, a longitudinal stationary toothed back section having a handle and an outstanding projection thereon, and a second longitudinal toothed back section having a depression therein and pivotally attached to said stationary toothed back section, said outstanding projection and said depression forming a locking means between said back sections when said pivotally attached back section is brought in alignment with said stationary back section, said projection and said depression being located between the pivotal connection of said sections and the handle.

15 3. In a comb, a main comb member having a back, teeth on said back and a handle extending from said back, a second comb member having a back and teeth on said back, means pivotally connecting said backs at points intermediate the ends thereof whereby said second comb member may be swung into and out of position lying against one side of said main member with the teeth of said members presented in parallel rows for a joint combing action, a projection on the back of one of said members adapted to engage the back of the other of said members when said members are in side by side position and operating to flex said members, said other member having a depression therein in which said projection extends to hold said comb members in said side by side relation; and a keeper member on said main comb member arranged to embrace the back of the second member to hold it in combing 20 30 35 40 relation to the main comb member.

ERNEST L. HOLLENBECK.
